ELECTRIC PLUG CONNECTION AND TERMINAL BOX

Paul Christ, New York, N. Y.

Application August 17, 1932, Serial No. 629,140

4 Claims. (Cl. 247—18)

This invention relates to electrical circuit terminal boxes and connecting plugs therefor, and more particularly to such devices related to locations where dampness or moisture exists and

5 where gases or explosive vapors regularly or intermittently permeate the atmosphere, as for example on ships, in refineries, gasoline filling stations or garages, paint works, or other places where an electric spark may cause an explosion.

10 The construction of such a device must be watertight in order to prevent the entrance of water or moisture to cause resulting corrosion or "short-circuiting" and gastight to prevent the entrance of explosive gases. Another important

15 requisite condition is an assurance that the cables and connections be entirely free from stresses or strains so that there will be no breaking or ruptures in the circuit at any point, and further it is important in the construction of such a device

20 that when contact is established the access of gas or explosive vapors to contact points in the socket be inhibited. In addition to the objects of providing a construction that will meet the foregoing conditions, another object of the invention is to

25 provide a simple construction adapted to reduce manufacturing costs, to facilitate the safe and facile making of connections, and to provide an electric socket which is universal to standard plugs so that it may be readily used when the

30 conditions of moisture or explosive atmosphere are absent, for the attachment of electrical devices carrying a standard plug.

Reference is now made to the drawing for illustration of a preferred embodiment of the invention in which

Fig. 1 is an elevation,

Fig. 2 is a vertical section, and

Fig. 3 is a plan view of the plug and cable with the cap removed.

40 The terminal box is adapted to lie against a wall A. The terminal box 8 is internally coated with a noncorrosive paint 25 to prevent rust and at the rear of the inside of the box is a cork absorption washer 9 on which is mounted the

45 terminal base 10 to which are secured the lead-in circuit wires 11 introduced from the conduit 7 which has a threaded connection with the box 8. The socket housing 12 is mounted on the base 10 and contains the conventional T-

50 shaped terminal apertures adapted to receive the T-shaped terminals 24 from the plug and to establish an electric circuit when these terminals are pushed fully home in the socket. It is readily understood that when these terminals enter the

55 apertures in the top of the socket they simul-

taneously cut off the potential access of any fluid or gas into the socket so that contact is actually established without any possibility of a spark igniting an explosive atmosphere. So also in removing the terminals 24 they lie in the socket 60 apertures for a safe and appreciable period of time after the breaking of the circuit. This construction positively eliminates any fire hazard at this time, and an added safeguard will be

discussed hereinafter. A cover plate 1 having an 65 externally screwthreaded neck portion is secured by screws 18 over the front of the terminal box 8 and is sealed by a fluid-proof gasket 19. The auxiliary cap 2 internally threaded and provided with a rubber sealing washer 21 is attached by 70 the chain 3 to the plate 1 and is always screwed over the neck of the plate when the cap 4 and the plug assembly shown in Fig. 3 are removed from the terminal box. The externally knurled cap 4 is snugly rotatable about the cylindrical 75

extension 23 of the plug housing or cap 13, and is adapted to contact a continuous-piece and fluid-tight spring washer 22 which overlies the flat shoulder formed between the plug housing 13 and the extension 23. It will now be readily understood that the cap 4 and the continuous spring washer 22 not only seal the terminal box 8 fluid-tight but also push home and hold secure the plug terminals 24 in the socket 12 causing an 80 easy thrust that prevents the twisting or straining of the terminals, and upon loosening the cap 4 by unscrewing it the spring washer 22 tends to keep the electric contact as the cap is unscrewed, thereby enhancing the rapidity of circuit-breaking. The housing 13 and the extension 23 are one integral brass shell having an integral externally threaded neck 20 on which is mounted an internally threaded and externally 85

knurled retainer ring 17 which is screwed down to overlie and be frictionally held against the shoulder formed between the extension 23 and the neck 20. The spacing between the cap 4 and the retainer ring 17 in relation to the distance x (Fig. 2) through which the cap 4 must be unthreaded 90 for disconnection from the neck of cover plate 1, and in further relation to the distance y representative of the contacting relation between the terminal points of the plug 24 and the terminals of the socket 10, is such that it is not possible to remove the cap 4 without the cap 95 initially abutting ring 17, thereafter lifting the plug housing 13 and so breaking the circuit at the terminals 24. In other words, the distance x through which the cap 4 is in threaded engagement with the neck of the cover plate 1 is at least 100

105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

as great as the distance in spacing between the cap 4 and the retaining ring 17, plus the distance y , the latter being representative of the depth of electrical contact between the terminal 5 points of the plug 24 and the terminals of the socket 10. The result of such proportioning is that terminal points 24 are electrically disconnected from the terminals of the socket 10 prior to full unthreading of the cap 4 from the cover 10 plate 1. No sparking in the socket can therefore be communicated to the outside atmosphere. Similarly in making contact in the socket it is required that the cap 4 be in screw-threaded engagement with the cover 1 before the terminal 15 points 24 are in the fixed contacting position.

The outlet cable 6 is passed through the top of the internally threaded and externally knurled sealing cap 5 which has on the inside of its cover a 45 degree truncated conical surface 16. The 20 cable next passes through a soft rubber bushing 14 the inner end of which is in the form of a truncated cone of steep pitch and the outer end 15 of which is in the form of a 45 degree truncated cone. The inside of the neck 20 has a slightly 25 conical seat 26 the importance of which in overcoming fire hazards arising from strained or mutilated connections in the plug will now become evident. The outer form of the soft rubber bushing 14 is such that as the sealing cap 5 is 30 turned home the bushing is not translated lengthwise within the neck 20 but rather is compressed laterally against the conical seat 26 and the seat 16 of the cap 5 and against the cable 6 from opposite directions lengthwise to hold the cable 35 securely in the fixed position so that external jerks or pulls will be absorbed entirely at the bushing 14, thereby absolutely relieving the connections of any stresses or strains and any consequent liability to mutilation.

40 To sum up: My improved device is simple in construction and therefore low in manufacturing cost; it is watertight and gastight; it provides for standard plug and socket equipment thereby further reducing manufacturing cost and providing 45 further for interchangeability; it provides for an ignition-proof make-and-break of the plug terminals and the socket both within the terminal box and against atmospheric gaseous mixture outside the box; and it assures freedom from strains 50 on all the electric connections.

Having now shown and described one embodiment of my invention, and realizing that in view of my disclosure modifications in details and dimensions of construction will readily occur to those skilled in the art but within the spirit and scope of my invention, I do not choose to be limited except as in the appended claims.

I claim:

60 1. A fluid-tight electric outlet device comprising a receptacle, an electrical socket member provided with terminals and mounted in the receptacle, the socket member being operative to receive the terminals of an electric plug, a cover plate for said receptacle having a tubular threaded extension therefrom, said plug being movable through said extension and including a cap having a tubular extension threaded for a portion of its length, an internally threaded retainer ring arranged on said plug cap extension, and a closure 65 cap apertured for the passage of the plug and

threaded on said threaded extension of the cover plate, said closure cap upon initial unthreading being operative to abut said retainer ring whereby to electrically disconnect the plug terminals from the socket terminals prior to full unthreading from the cover plate extension. 80

2. A fluid-tight electric outlet device comprising a receptacle, an electrical socket member provided with terminals and mounted in the receptacle, the socket member being operative to receive the terminals of an electric plug, a cover plate for said receptacle having a tubular threaded extension therefrom, said plug being movable through said extension and including a cap having a tubular extension and a threaded neck extending therefrom, with a shoulder intermediate said cap extension and said neck, a retainer ring operatively arranged on said neck and engaging said shoulder, and a closure cap apertured for the passage of the plug and threaded on said threaded extension of the cover plate, said closure cap upon initial unthreading being operative to abut said retainer ring whereby to electrically disconnect the plug terminals from the socket terminals prior to full unthreading from the cover 90 plate extension. 95

3. A fluid-tight electric outlet device comprising a receptacle, an electrical socket member provided with terminals and mounted in the receptacle, the socket member being operative to receive the terminals of an electric plug, a cover plate for said receptacle having a tubular threaded extension therefrom, said plug being movable through said extension and including a cap having a tubular extension threaded for a portion of its length, an internally threaded retainer ring arranged on said plug cap extension, and a closure cap apertured for the passage of the plug and threaded on said threaded extension of the cover plate, and normally spaced from the retainer ring, the depth of threaded engagement of the closure cap with the threaded extension of the closure plate being greater than the normal spacing between the closure cap and the retainer ring plus the effective depth of electrical contact between the terminals of said socket and said plug. 100

4. A fluid-tight electric outlet device comprising a receptacle, an electrical socket member provided with terminals and mounted in the receptacle, the socket member being operative to receive the terminals of an electric plug, a cover plate for said receptacle having a tubular threaded extension therefrom, said plug being movable through said extension and including a cap having a tubular extension threaded for a portion of its length, with a shoulder intermediate the cap proper and the extension, a retainer ring threaded on said cap extension, a closure cap apertured for the passage of the plug and threaded on said threaded extension of the cover plate, a fluid-tight spring washer on the cap extension disposed between said closure cap and said shoulder of the plug cap, said closure cap upon initial unthreading being operative to abut said retainer ring whereby to electrically disconnect the plug terminals from the socket terminals prior to full unthreading from the cover plate extension. 110
